UNITED STATES PATENT OFFICE.

ORVILLE S. HALL, OF CANTON, OHIO.

RAILWAY-RAIL.

1,175,758.

Specification of Letters Patent. Patented Mar. 14, 1916.

Application filed August 29, 1914. Serial No. 859,188.

To all whom it may concern:

Be it known that I, ORVILLE S. HALL, a citizen of the United States, residing at Canton, in the county of Stark and State of Ohio, have invented new and useful Improvements in Railway-Rails, of which the following is a specification.

The present invention relates to improvements in means for connecting the meeting ends of two railway rails, the primary object being to provide a simple, comparatively cheap and thoroughly effective device whereby the said rails will be effectively and securely connected.

With the above and other objects in view, the improvement resides in the construction, combination and arrangement of parts set forth in the following specification and falling within the scope of the appended claim.

In the drawings: Figure 1 is a side elevation of a rail joint constructed in accordance with the present invention, Fig. 2 is a similar view but looking toward the opposite side, Fig. 3 is a top plan view of the same, Fig. 4 is a sectional view on the line 4—4 of Fig. 3, Fig. 5 is a similar sectional view on the line 5—5 of Fig. 3, Fig. 6 is a horizontal sectional view on the line 6—6 of Fig. 1, Fig. 7 is a longitudinal sectional view approximately on the line 7—7 of Fig. 3, Fig. 8 is a perspective view of the chair member, Fig. 9 is a similar view of one of the wedge plates, and Fig. 10 is a similar view of one of the rail ends.

Referring now to the drawings in detail, 1—1 designate the ends of two abutting rails. These rails are of the ordinary construction, and in the present instance the 40 said rails have their webs from their ends provided with longitudinally extending slots or openings 2 and their webs further provided with one or more bolt openings arranged at the rear of the slot. The joint 45 includes a chair 3 which is provided with a horizontally straight base 4, and one of the longitudinal edges of said base is formed with an inwardly extending angular flange 5 which terminates in a vertical longitudinally extending plate 6. The flange 5 is 50 adapted to overlie and engage with the base flanges of the rails, when the said rails are arranged upon the chair, while the plate 6 engages within the fishing spaces of one of 55 the sides of the rails. The plate 6, in the present instance, is centrally enlarged or

thickened, as at 7. Formed upon the upper edge of the plate 6 and extending longitudinally therewith is a crest 8, the said crest being of a maximum thickness at the central portion of the chair, and having its outer face inclined in opposite directions to the ends thereof. The vertical plate is provided with one or more bolt openings 9 which are preferably arranged adjacent the outer ends thereof, and the longitudinal outer edge of the base provided with the rail engaging members, just described, is formed with bosses 10, whereby the vertically arranged openings 11 may be provided at the longitudinal edges of the rail base, so that spikes 12 passing through the said openings and into the ties 13, will contact with the longitudinal edges of the base flanges of the rails 1. The meeting ends of the rails are 70 adapted to be arranged central of the chair and therefore central of the crest 8, and the upper face of said crest, at the central portion thereof, preferably extends a slight but suitable distance above the heads of the 80 rails, the said upper face being inclined in opposite directions from the central portion and the projecting portion of the crest provides a bearing surface for the treads of the wheels of the rolling stock to overcome 85 the liability of the tipping of the said rail ends as well as the shock and jar incident to the passage of the wheels over the gap at the rail ends.

The base 4 of the chair 3 is provided 90 upon its opposite longitudinal edge with a rail engaging short side or flange 14, the same including a vertical extension or plate. The short, flanged side member 14 is comparatively thick, and the opposite ends 95 thereof are formed upon their inner faces with grooves or pockets 16 which correspond to the inner contour of the said flange or side. The vertical member or plate of the side 14 below its rail head engaging edge 100 is connected with the plate 6 by a longitudinally extending web 17, the said web being of a length equaling the length of the inner face of the said vertical member or plate between the end grooves or depression 16. The longitudinal edge of the base 4 has suitable spike openings 18 which are 105 preferably arranged adjacent the opposite corners of the said plate at the opposite ends of the short side or flange 14, and through which the spikes 12 pass.

The rails are moved upon the base 4 of

the chair toward each other, so that the web 17 will be received within the slots 2 of the said rails and their bolt openings align with the bolt openings in the plate 6. 5 When the rails are thus positioned, angular side wedge members 19 and 20 respectively are arranged upon the base at the opposite sides of the flange 14. These members 19 and 20 have their inner faces shaped 10 to conform to the shape of the rails against which they are adapted to be arranged, and the vertical plates of the said members are provided with bolt openings which are adapted to register with the bolt openings 15 in the webs of the rails and the bolt openings in the said plate 6. The lower and outer edges of the said members 19 and 20 are provided with notches 21 which are adapted to register with the spike openings 18 in the base 4, and one end of each 20 of the said members 19 and 20 is adapted to be forced into one of the oppositely disposed grooves or pockets 16 formed upon the central member provided by the flange 25 14. It should here be stated that the ends of the members 19 and 20 which engage with the longitudinal walls provided by the groove or pocket may be wedge-shaped as may also the said longitudinal walls of the 30 pockets, so that the members 19 and 20 will be forced into tight contact with the rails 1-1 when positioned upon the chair. Bolts 23 are passed through the openings in the members 19-20, the plate 6 and the 35 webs of the rails, nuts 24 engaging the said bolts to retain the same upon the joint. The outer faces of the angular flange 5 and the flanged portions of the members 19 and 20 may engage with one of the edges of 40 the nuts as illustrated in the drawings, in

which instance the heads of the bolts must necessarily be provided with slots or grooves for the reception of driving means, and this arrangement will effectively prevent the nuts from working loose from the bolts. 45

Having thus described the invention, what I claim is:

In a rail joint, the combination with the meeting ends of two rails each having its web slotted longitudinally from its end, of 50 a chair, said chair including a base upon which the rails rest, the chair having one of its edges formed with a flange, the inner face of which being shaped to engage with the rails within the fishing spaces, the opposite longitudinal edge of the chair being centrally formed with a comparatively short 55 side flange which has its inner face shaped to engage with the base flange and within the fishing spaces of the rails, said short 60 side having its edges formed with pockets, a horizontally disposed longitudinally extending web disposed between the pockets of the short side and connecting said short side flange with the long side flange of the chair, 65 angular wedge plates engaging the sides of the rails inserted within the pockets from the opposite ends of the short side of the chair, the said wedge members having securing means passing laterally through the 70 wedge members and the webs of the rails alongside of the chair, and vertically arranged means for securing the wedge members to the base of the chair.

In testimony whereof I affix my signature 75 in presence of two witnesses.

ORVILLE S. HALL.
